UNITED STATES PATENT OFFICE.

MAYER GRANAT, OF SAN FRANCISCO, CALIFORNIA.

NOZZLE FOR TOBACCO-BAGS.

No. 806,084.

Specification of Letters Patent.

Patented Nov. 28, 1905.

Application filed May 24, 1905. Serial No. 261,982.

To all whom it may concern:

Be it known that I, MAYER GRANAT, a citizen of the United States, residing at San Francisco, in the county of San Francisco and State of California, have invented new and useful Improvements in Nozzles for Tobacco-Bags, of which the following is a specification.

My invention pertains to normally closed discharge-nozzles for tobacco-bags and the like; and it consists in the peculiar and advantageous nozzle hereinafter described, and particularly pointed out in the claim appended.

In the accompanying drawings, forming part of this specification, Figure 1 is a longitudinal section illustrating my novel nozzle properly arranged relative to a tobacco-bag and connected thereto. Fig. 2 is an enlarged perspective view of the nozzle as it appears when removed from the bag. Fig. 3 is a top plan view of the nozzle, and Fig. 4 is an inverted plan view of the same.

Similar letters designate corresponding parts in all of the views of the drawings, referring to which—

25 A is a tobacco-bag, of textile or other soft material, having the usual mouth *a* and drawstring *b* for contracting the mouth, and B is my novel nozzle as a whole. The said nozzle is preferably of metal and is made up of a lever-section C, a lever-section D, a transverse pintle E, pivotally connecting the said lever-sections together, and a coiled spring F for returning the lever-sections to and normally retaining said sections in their closed positions, the said spring being coiled about the pintle E and having terminal arms *c* exerting constant pressure against the inner portions of the lever-sections C and D, as best shown in Fig. 4.

40 The lever-sections C and D, respectively, comprise a flat outer arm *d*, which is normally inclined inwardly and is provided with a square upper edge *e* and a vertical base *f*, side flanges *g* extending inwardly at right angles from the arm *d* and the base *f* and having their upper edges rounded, as indicated by *h*, parallel horizontal flanges *k* extending laterally from the base *f* and the side flanges *g*, and an inner arm *m* fixed with respect to the outer arm.

45 50 The arm *d* of the section D is, however, of a less width than the arm *d* of the section C, and hence is adapted to normally rest within and against the latter arm after the manner shown.

55 My novel nozzle is applied in the manner

shown in Fig. 1—that is to say, the wall of the bag-mouth is disposed in the groove formed by the flanges *k* of the nozzle and is drawn taut about the nozzle through the medium of the string *a*. With the nozzle applied as stated 60 tobacco can only escape from the bag through the nozzle, and then only when the outer arms *d* of the lever-sections C and D are moved apart by inward pressure exerted against the inner arms *m* thereof. When the supply of 65 tobacco in the bag is exhausted, the bag may be readily replaced with a full bag or else the outer arms *d* of the lever-sections C and D may be held apart by pressure applied to the inner arms *m* and the original bag refilled with 70 tobacco through the nozzle.

As will be readily gathered from the foregoing, the outer portion of each of the lever-sections of the nozzle is of an even width throughout its length and is provided with a 75 free end or edge which is square—*i. e.*, straight and disposed at right angles to the length of the nozzle. From this it follows that when the outer arms of the lever-sections are moved apart a large passage is afforded for the 80 tobacco in discharging a bag or refilling the same.

It will also be gathered from the foregoing that the terminal arms of the coiled spring bear upwardly against the bases *f* of the arms 85 *d*, and hence are enabled to exert considerable leverage, with the result that the free upper ends or edges of the lever-sections are tightly held together, so as to preclude the 90 casual escape of tobacco.

It will be further noticed that my novel nozzle is compact and is well adapted to withstand the usage to which such devices are ordinarily subjected.

Having described my invention, what I 95 claim, and desire to secure by Letters Patent, is—

A normally closed, discharge-nozzle for tobacco-bags and the like, comprising two lever-sections each of which has an outer, flat, 100 inwardly-inclined arm the free edge of which is square, a vertical base at the inner end of said arm, side flanges extending inwardly at right angles from the outer arm and the vertical base and tapered toward their upper 105 ends, flanges extending laterally from the vertical base and the lower portions of the side flanges and an inner arm fixed with respect to the outer arm; the outer portion of one of said lever-sections being of a less width than 110

the outer portion of the other so as to normally rest within the latter portion, a pintle extending through the lower portions of the side flanges of the lever-sections and pivotally connecting said sections together, and a coiled spring mounted on the pintle and having terminal arms bearing upwardly against the bases of the outer arms of the lever-sections.

In testimony whereof I have hereunto set my hand in presence of two subscribing witnesses.

MAYER GRANAT.
